(57) **CLAIM**

The ornamental design for an ergonomic tool handle, as shown and described.

DESCRIPTION

FIG. 1 is a front perspective view of an ergonomic tool handle with a collapsible, lower handle part in an operative position, showing my new design;

FIG. 2 is a right side view thereof;

FIG. 3 is a left side view thereof;

FIG. 4 is a front elevation view thereof;

FIG. 5 is a rear elevation view thereof;

FIG. 6 is a top plan view thereof;

FIG. 7 is a bottom plan view thereof; and,

FIG. 8 is a front perspective view of the ergonomic tool handle with the collapsible, lower handle part in a collapsed, inoperative position.

The broken line showing of the broom depicts environment of the ergonomic tool handle and forms no part of the claimed design.
